7 Claims. (Cl. 100—214)

ABSTRACT OF THE DISCLOSURE

A spindle press in which a ram has upstanding front and rear wings which bracket a cross-piece of the frame and have vertical edges in sliding contact with that cross-piece; these wings have a height greater than a vertical ram stroke to straddle the cross-piece in top and bottom positions of the spindle, the frame having a pair of uprights with the cross-piece attached to their upper ends. The uprights and cross-piece have aligned front and rear shoulders constituting vertical guideways for the ram.

My present invention relates to a spindle press of the general type described, for example, in commonly assigned application Ser. No. 550,208, filed May 16, 1966, by Volker Stille and me.

In such press a spindle is mounted, generally vertically, in a frame which threadedly engages, usually through the intermediary of a stationary nut, so as to move up and down upon being reversibly rotated, the lower end of the spindle carrying a ram to be brought into contact with a workpiece carried on the press frame. In order to impart such reversible rotation to the spindle, the latter is rigid with a driven disk which is frictionally engageable by either one of two driving disks flanking the spindle. The driving disks can thus be jointly and continuously rotated by an appropriate power source, such as an electric motor, so that a large torque is instantly available for transmission to the driven disk as soon as the latter makes contact with one of the driving disks; as the spindle descends, the driven disk engages the cooperating driving disk along an ever-increasing radius so as to be progressively accelerated during the working stroke of the ram.

If a press of this description is to produce a large output, the motion of the spindle must be reversed at a rapid rate. Such rapid reversals, however, are possible only if the spindle and its ram together have a low inertia, this in turn calling for a ram of limited height. On the other hand, it is necessary that the ram be accurately guided on the press frame, such guidance being difficult to achieve with rams of short axial length.

My present invention, accordingly, has for its object the provision of an improved ram construction which affords accurate guidance while allowing a substantial reduction in the overall dimensions and, therefore, the weight of the ram as compared with conventional presses of this type.

The above object is realized, pursuant to my present invention, by the provision of a ram having upstanding front and rear wings which bracket a cross-piece of the frame and have vertical edges in sliding contact with that cross-piece, these wings advantageously having a height greater than a vertical ram stroke so as to straddle the cross-piece in both a top and a bottom position of the spindle.

In a preferred embodiment, pursuant to a further feature of my invention, the frame comprises a pair of uprights having the cross-piece fixed to their upper ends, the uprights and the cross-piece being formed with aligned front and rear shoulders which constitute vertical guide-

2

ways for the ram. Advantageously, these guideways accommodate respective guide rails for the ram which span both the uprights and the cross-piece so as to avoid any discontinuity along the ram stroke.

5 The above and other features of my invention will become more fully apparent from the following detailed description, reference being made to the accompanying drawing in which:

FIG. 1 is a front-elevational view of a spindle press embodying the invention;

10 FIG. 2 is a cross-sectional view, drawn to a larger scale, on the line II—II of FIG. 1;

FIG. 3 is a sectional elevational view taken on the line III—III of FIG. 1;

15 FIG. 4 is a cross-sectional view drawn to substantially the same scale as FIG. 2 and taken on the line IV—IV of FIG. 1; and

FIG. 5 is a side-elevational view of a ram forming part of the press shown in FIGS. 1—4.

20 The press shown in the drawing comprises a frame with a pair of uprights 1 bridged by a cross-piece 2. Lodged centrally in this cross-piece is a fixed nut 4 threadedly receiving a vertical spindle 5 whose lower end is rigid with a ring 9 held axially between a pair of thrust bearings 7 and 10. The bearings are seated in a ram 6, upper bearing 7 being locked in position by a collar 8 which is fastened to the ram by screws 8'. Tie rods 3 extend vertically within the uprights 1 and have heads 3' bearing upon the cross-piece 2, their lower ends being secured by nuts 61 to a base 60 forming part of the press frame.

25 The ram 6 is of generally cup-shaped configuration and has a bottom 14 of limited thickness integral with a pair of upstanding front and rear wings 15. These wings bracket confronting cylindrical outer surfaces 2' of the cross-piece 2, centered on the axis of spindle 5, and are in sliding contact with both the cross-piece 2 and the uprights 1. This sliding contact takes place through the intermediary of a set of rails 22 of triangular profile, resting against aligned front and rear shoulders 20, 20a of the cross-piece and the uprights, and vertical bars 23 of square profile which are rigid with the ram and are received in V-grooves 17 along the lateral edges of the wings 15. The rails 22 extend over the full stroke length of the ram which is so dimensioned that the wings 15

30 still straddle the cross-piece 2 in the lowermost spindle position in which the ram bottom 14 is at a level shown in dot-dash lines in FIG. 1. The guide surfaces of these rails, contacted by the bars 23, lie in generally diagonal vertical planes which pass close to the axis of spindle 5.

35 The ram bottom 14 has a central recess 16 for the attachment of tools designed to deform a workpiece resting on the bed 16. Guard strips 24 are secured to the cross-piece 2 by screws 24' and overlie the bars 23 which in turn are attached to the ram 6 by countersunk screws 23' received in threaded bores 27.

40 The tube of spindle 5 is rigid with a driven disk 11 alternately engageable by a pair of driving disks 29a, 29b on a horizontal shaft 30; the unit 29a, 29b, 30 is journaled in fixed bearings 51 atop the frame 1, 2 and is axially shiftable for selective frictional contact of disk 11 with either of disks 29a, 29b. In operation, the unit 29a, 29b, 30 is continuously rotated by a drive motor 53 via a belt 54 on disk 29b.

45 As seen most clearly in FIG. 5, the ram 6 has lateral cutouts 28 separating the wings 15 from each other. The wings are formed with large openings 13 which further reduce the weight of the ram and facilitate visual inspection of the spindle 5 at the point of its emergence from nut 4.

50 Only the rails 22, forming continuous guideways for the ram, the bars 23 in contact therewith and the associated guard strips 24 need to consist of highly polished

bearing metals; the other surfaces of the ram and the frame do not require special machining.

Transparent window panes 13' of light-weight material in openings 13 enable the wings 15 to act as shields which intercept outwardly squirting oil during reciprocation of the ram.

It will be apparent that even substantial eccentric stresses exerted upon the ram will be absorbed by the sliding mounting described and illustrated so that no wedging or jamming of the reciprocating assembly will occur.

I claim:

1. In a spindle press, in combination, a frame comprising a pair of lateral uprights and a cross-piece bridging said uprights; a vertical spindle flanked by said uprights and threadedly received in said cross-piece for co-ordinated rotation and vertical motion; drive means supported on said frame for reversibly rotating and thereby alternately lowering and raising said spindle between a top position and a bottom position hereof; and a vertically movable ram mounted on the lower end of said spindle for vertical entrainment thereby, said ram being provided with upstanding front and rear wings bracketing said cross-piece and having vertical edges in sliding contact with the latter and with said uprights.

2. The combination defined in claim 1 wherein said wings have a height greater than the vertical stroke of said ram, thereby straddling said cross-piece in both said top and bottom positions of said spindle.

3. The combination defined in claim 1 wherein said cross-piece is fixed to the upper ends of said uprights, said

uprights and said cross-piece being formed with aligned front and rear shoulders constituting vertical guideways for said ram.

5 4. The combination defined in claim 3, further comprising a set of vertical guide rails for said ram fixedly received in said guideways and spanning the respective uprights and said cross-piece.

5 5. The combination defined in claim 4 wherein said guide rails have ram-engaging faces lying in generally diagonal vertical planes.

10 6. The combination defined in claim 5, further comprising a set of guard strips carried on said cross-piece and forming vertical guide channels with said ram-engaging faces of said rails, said ram being provided with front and rear lateral projections respectively received in said channels.

15 7. The combination defined in claim 6 wherein said projections are formed by vertical bars of substantially square profile rigid with said ram.
